UNITED STATES PATENT OFFICE.

JOSEPH MAZER, OF McALESTER, OKLAHOMA.

WINDING-INDICATOR.

1,265,802.

Specification of Letters Patent.

Patented May 14, 1918.

Application filed March 1, 1913, Serial No. 751,472. Renewed March 19, 1918. Serial No. 223,478.

To all whom it may concern:

Be it known that I, JOSEPH MAZER, a citizen of the United States, and resident of McAlester, in the county of Pittsburg and State of Oklahoma, have invented a new and useful Improvement in Winding-Indicators; and I do hereby declare the following to be a full, clear, and exact description thereof.

My invention relates to winding indicator mechanism for watches, graphophones or other devices, which indicates to what extent the device is run down and when it needs winding up.

The object of the invention is to provide a simple and effective form of mechanism for this purpose which can be located in the ordinary watch movement (when it is applied to a watch) without increasing the size of the space required for such movement and without the necessity of changing materially the standard construction.

To these ends my invention comprises the novel features hereinafter set forth.

In the accompanying drawing Figure 1 is a face view of a watch with my invention applied thereto; Fig. 2 is an enlarged view of a portion of the back of the movement; Fig. 3 is a reverse view to that shown in Fig. 2; Fig. 4 is a section on the line 4-4 Fig. 2; and Fig. 5 shows an enlarged section of the reversing mechanism.

In the drawing I have illustrated my invention as applied to a watch, although it may be applied to graphophones or other devices. The letter A indicates the bottom plate of the watch, and B the top plate. The numeral 2 designates the pinion on the winding stem meshing with the crown teeth of the crown wheel 4. The teeth 3 of the crown wheel mesh with the ratchet wheel 5 held against rotation in one direction by a suitable pawl. The ratchet wheel is held down by the screw 7 which passes into the arbor 12 of the main spring barrel. A double pinion 9^a has one set of teeth 9 meshing with the ratchet wheel and the other set of teeth 10 meshing with the gear wheel 11. This gear wheel 11 has the pivot 27 which is journaled in the bridge 31. The crown teeth 18 of the gear wheel 11 mesh with the teeth 17 of the double planet pinion 16^a. This planet pinion 16^a is loosely mounted on the screw 19 which is screwed into the rotating member 20. This rotating member or disk 20 is cut away as at 20^a to receive

the planet pinion 16^a. The disk 20 has the journal portion or arbor 21 which extends into the bottom plate A and said arbor carries the pinion 22. A gear wheel 14 fits loosely around the arbor 21 and this gear wheel is spaced from the gear 11 by the disk 20. The gear wheel 14 meshes with the spring barrel 13. The crown teeth 15 of the gear wheel 14 mesh with the teeth 16 of the planet pinion 16^a. By having the disk member 20 recessed as at 20^a I am enabled to place the planet pinion over toward the center and save space, while at the same time the gear wheel 14 mounted on the arbor 21 will always have a bearing without regard to how far the planet pinion may extend toward the center. The disk 20 by filling the space between the wheels 14 and 11 acts to separate these wheels so as to permit the free movement of the planet pinion 16^a.

The pinion 22 meshes with the gear wheel 23 which has a pinion portion 24 which meshes with the indicator hand wheel 25, carrying the indicator hand 26.

In certain watches, such as that illustrated, there is a slot 28 or separation in the bridges of the upper plate, one side of this slot 28 being in this case the end of the barrel bridge 29 and the other side being the beginning of the balance bridge 30. The bridge 31 is held down on the barrel bridge 29 by the screws 32 and said bridge 31 forms the bearing for the pivot 27 which is the center of the entire planetary system.

When the watch is being wound the wheel 14, being connected with the main spring barrel 13 remains relatively still. Motion is imparted to the bevel pinion 2 which meshes with the crown teeth of the crown wheel 4 which meshes with the ratchet wheel 5, which in turn rotates the double pinion 9^a. In this way rotary movement is imparted to the planetary wheel 11 whose crown teeth 18 mesh with the teeth 17 of the planet pinion 16^a. As the gear wheel 14 is held stationary the planet pinion 16^a meshing with the crown teeth 15 of said gear wheel revolves around on the inside of said wheel, carrying with it the disk member 20. The rotation of the disk member carrying the pinion 22 in turn rotates the gear wheel 23 and through the pinion 24 the hand indicator wheel 25, until the indicator hand is returned to zero.

When the watch is running the planetary

wheel 11 is held stationary through its connection with the ratchet wheel and the gear wheel 14 is rotated by the barrel 13. The crown teeth 15 of the wheel 14 mesh with the teeth 16 of the planet pinion 16^a and with the gear wheel 11 held stationary the planet pinion rotates around with its teeth 17 meshing with the teeth 18 of the gear wheel 11. In this manner the reverse movement is imparted to the rotary disk 20 and through the train of gearing described the hand wheel is moved from zero around the dial, indicating the amount the watch has run down.

By the above construction the indicating mechanism is located within a limited space and may be inserted without changing the watch movement. In removing the planetary system from the watch it is not necessary to remove the pinion 22 from the arbor, as it is drawn right down through the opening without the necessity of removing any parts from the arbor.

What I claim is:

1. In winding indicator mechanism, the combination of a main-spring barrel, winding mechanism including a ratchet-wheel, a gear-wheel, connections between said gear-wheel and the ratchet-wheel, a rotary disk member, a double planetary gear carried by said disk, said planet-gear meshing with said gear-wheel, a second gear wheel separated from the first gear-wheel by said rotary disk member, said second gear being engaged by the teeth of said double planet pinion, connections between said second gear wheel and the main-spring barrel, an arbor on said rotary disk member forming a bearing for said second gear wheel, a pinion on said arbor adapted to pass through the opening through which said arbor is inserted, an indicator-hand wheel, and connections between said pinion and said indicator-hand wheel.

2. In winding indicator mechanism, the combination of a main-spring barrel, winding mechanism including a ratchet-wheel, a gear-wheel, connections between said gear-wheel and the ratchet-wheel, a rotary disk member having a recessed portion, a double planetary gear carried by said disk in said recessed portion, said planet gear meshing with said gear-wheel, a second gear wheel separated from the first gear-wheel by said rotary disk member, said second gear being engaged by the teeth of said double planet pinion, connections between said second gear wheel and the main-spring barrel, an arbor on said rotary disk member forming a bearing for said second gear wheel, a pinion on said arbor adapted to pass through the opening through which said arbor is inserted, an indicator-hand wheel, and connections between said pinion and said indicator-hand wheel.

3. In winding indicator mechanism, the

combination of a main-spring barrel, winding mechanism including a ratchet-wheel, a gear-wheel, connections between said gear-wheel and the ratchet-wheel, a rotary disk member having a recessed portion, a double planetary gear carried by said disk in said recessed portion, said planet gear meshing with said gear-wheel, a second gear wheel separated from the first gear-wheel by said rotary member, said second gear being engaged by the teeth of said double planet pinion, connections between said second gear wheel and the main-spring barrel, an arbor on said rotary disk member forming a bearing for said second gear wheel and extending through the watch plate, a pinion on said arbor adapted to pass through the opening through which said arbor is inserted, an indicator-hand wheel, and connections between said pinion and said indicator-hand wheel.

4. In indicator winding mechanism, the combination of the main-spring barrel, winding mechanism including a ratchet-wheel, a gear wheel having crown teeth, connections between said gear wheel and the ratchet-wheel, a rotary disk member having a recessed portion and located within the crown teeth of said gear, a double planet gear carried by said disk-member in said recessed portion, the crown teeth of said gear wheel internally meshing with one set of the teeth of said double planet gear, a second gear wheel spaced from said first gear wheel by said disk-member, connections between said second gear wheel and the main-spring barrel, said second gear wheel having crown teeth meshing internally with the second set of teeth in said double planet gear, an arbor on said rotary disk member forming a bearing for said second gear wheel, a pinion on said arbor, an indicator-hand wheel, and connections for said pinion and said indicator-hand wheel.

5. In indicator winding mechanism, the combination of the main-spring barrel, winding mechanism including a ratchet-wheel, a gear wheel having crown teeth, connections between said gear wheel and the ratchet-wheel, a rotary disk member having a recessed portion and located within the crown teeth of said gear, a double planet gear carried by said disk-member in said recessed portion, the crown teeth of said gear wheel internally meshing with one set of the teeth of said double planet gear, a second gear wheel spaced from said first gear wheel by said disk-member and of greater diameter than said first gear wheel, connections between said second gear wheel and the main-spring barrel, said second gear wheel having crown teeth meshing internally with the second set of teeth in said double planet gear, an arbor on said rotary disk member forming a bearing for said second gear wheel.

wheel, a pinion on said arbor, an indicator-hand wheel, and connections for said pinion and said indicator-hand wheel.

6. In winding indicator mechanism, the combination of the top and bottom plates on which the mechanism is mounted, a main-spring barrel, winding mechanism including a ratchet-wheel, a gear-wheel with crown teeth having a bearing in one of said plates, 10 connections between said gear-wheel and the ratchet-wheel, a rotary disk-member, a double planetary gear carried by said disk member, said planet-gear meshing internally with the crown teeth of said gear-wheel, a 15 second gear-wheel with crown teeth sepa-

rated from said first gear by said disk-member, said second gear being internally engaged by the teeth of said planet-gear, connections between said second gear and the main-spring barrel, an arbor on said disk 20 forming a bearing for said second gear, a pinion on said arbor, an indicator-hand wheel, and connections between said pinion and said indicator-hand wheel.

In testimony whereof I, the said JOSEPH 25 MAZER, have hereunto set my hand.

JOSEPH MAZER.
